UNITED STATES PATENT OFFICE

LOUIS PAT, OF CHICAGO, ILLINOIS

WINDOW FASTENER

Application filed July 17, 1931. Serial No. 551,482.

This invention is directed to an improvement in window fasteners, and particularly to a means by which either sash may be moved relative to the other and locked at an appropriate point, the locking means serving to maintain the sash elevated and at the same time prevent its further elevation.

The primary object of the present invention is the provision of a window locking means embodying two elements to be respectively connected to the sash, these elements cooperating to lock the sash against further upward movement at any particular point, while permitting the sash to be moved freely downwardly at any time, the elements being further provided for such cooperation that the sash may be locked against relative movement when the window is closed.

The invention is illustrated in the accompanying drawing, wherein:—

Fig. 1 is a view illustrating the application of the window fastener.

Fig. 2 is a central vertical section.

Fig. 3 is a detail perspective view of the bracket.

Fig. 4 is a detail elevation of the locking pin.

Fig. 5 is a section of same on lines 5—5 of Fig. 4.

Fig. 6 is a detail view of the spring.

The improved locking means comprises a narrow metallic strip 1 formed at the respective ends with openings 2 for the reception of screws whereby it may be secured vertically of one of the side frame bars 3 of the upper sash of a window. This strip is formed with a lower locking opening 4 and with similar openings 5 at preferably uniformly spaced intervals throughout the length of the strip.

Above the locking opening the material of the strip in line with the particular opening 5 is formed as a channel 6, the bottom 7 of which inclines from the inner surface of the strip 1 to approximately the plane of the outer edge of the opening 5. In other words, the strip is formed with a series of channels leading to each of the openings 5, the bottom of which channels at their entrant or lower ends are coincident with the inner surface of the strip 1 and from which ends the bottoms

of the channels incline upwardly and inwardly to substantially the bottom of the particular opening 5.

The cooperating member of the locking means includes a bracket 8 of right angle form, the upright section 9 of which is channeled at 10 to slidably fit over the section 1. The remaining portion 11 of the bracket 8 is at right angles to the portion 9 and is formed with openings 12 for the reception of screws whereby the bracket may be secured to the upper bar 13 of the lower sash. The portion 9 of the bracket is formed near its upper end with an opening 14 in which is fitted a pin 15, preferably provided with an inclined terminal 16 and a button head 17. The pin beneath the button head 17 is circumferentially channeled at 18 to permit the engagement of one end of a spring 19 therewith, the spring being formed with a U-recess 20 in its upper end to fit in the channel 18. The opposite end of the spring is secured at 21 to the outer surface of the portion 9 of the bracket 8, the spring functioning to hold the pin in the opening 14, with its terminal 16 projected beyond the inner surface of the bracket. The portion 9 of the bracket is further formed in transverse alignment with the opening 15 with depressions 22 to provide for holding the pin in inoperative position, as will later appear.

With the parts in applied position, it will be understood that the bracket 8 is slidably cooperating with the strip 1 so that in the movement of the lower sash with respect to the upper sash the bracket 8 slides vertically of the strip 1. During the upward movement of the lower sash, the pin 15 is withdrawn sufficiently to allow the terminal 16 to be flush with the inner surface of the portion 9 of the bracket 8, and when the lower sash has reached the desired elevation, the pin is released and the terminal 16 seats in the adjacent opening 5 which, of course, provides a direct abutment against a further elevation of the lower sash. Thus, the lower sash is locked against being raised any further, though it may be moved downwardly without attention on the part of the operator with respect to the pin 17, as the inclined ter-

- 5 minal 16 of the pin rising on the inclined bot-
tom 7 of the channel 6 will ride over the
various openings 5 until the sash is complete-
ly lowered or interrupted at such lowering
5 in line with any particular opening 5. That
is to say, the sash when elevated may be
lowered to any desired extent and again
locked against further elevation in such de-
sired position.
- 10 10 The channel 18 in the pin 15 is formed
partly around the pin, leaving an elongated
section 24 transversely of the pin, the side
walls of which section are engaged by the
sides of the recess 20 to thus prevent turning
15 15 of the pin. Therefore, the inclined terminal
of the pin is always in position to cooperate
with the inclined bottoms 7 of the channels 6.
When the lower sash has been completely
20 20 lowered, that is, the window is completely
closed, the pin 15 will engage in the opening
4, forming a permanent lock against move-
ment of the sash in the upward direction
without withdrawing the pin 15.
- 25 25 When it is desired to dispense with the
function of the lock, the pin 15 is bodily with-
drawn from the opening 14 against the ten-
sion of the spring 19 and moved slightly to
one side to seat in one or the other of the
30 30 depressions 23. The pin is thus held from
any possible co-operation with the locking
strip and the sash is free to move without
regard to any locking means whatsoever.
- 35 35 The various parts are preferably construct-
ed of metal or other appropriate material
and are further made sufficiently light to
avoid appreciable obstructions on the win-
dow and yet of requisite strength to resist
attempts to move the window against the
locking means.
- 40 40 I claim:—
1. A window locking means including a
strip to be secured to the upper sash, a bracket
to be secured to the lower sash, said bracket
having edge flanges to form a guide for the
45 45 strip, said strip being formed with a plu-
rality of vertically spaced openings and with
a channel leading to each opening and hav-
ing a bottom inclined upwardly and out-
wardly with respect to the face of the strip, a
50 50 pin operating through the bracket and hav-
ing an inclined terminal, a pivotally mount-
ed spring engaging the pin for normally
maintaining the terminal projected in posi-
tion to engage with any of the openings in
55 55 the strip, and means on the strip in which the
pin may be laterally moved with the spring
and locked to hold the pin out of cooperation
with the strip.
- 60 60 2. A locking means for windows compris-
ing a narrow strip formed with an opening
near its lower end, a series of vertically
spaced openings above said lower opening,
the strip being further formed with a channel
65 65 leading to each of said vertically spaced open-
ings and having a bottom inclined upwardly
- and toward the bottom of the particular
opening, a bracket channeled to slidably co-
operate with the strip, a spring pivoted to
the bracket and bifurcated at its upper end,
a pin having a groove to receive the bifur-
cated end of the spring, said pin operating
through the bracket and having an inclined
terminal to cooperate with the inclined bot-
toms of the channels in the downward move-
ment of the bracket with respect to the strip,
said pin seating in any of the vertically spaced
openings to prevent upward movement of the
bracket without interfering with its free
downward movement, said pin being further
adapted to seat in the lower opening of the
strip to lock the bracket with respect to the
strip, said bracket being formed with depres-
sions in which when the pivoted spring is
swung laterally the pin may be seated to hold
the same free of cooperation with the strip.
- 70 70 In testimony whereof I affix my signature.
